COUNTER MEANS FOR COIN CHUTES

Harvey N. Bliss, Windsor, Conn., assignor to
Veeder-Root Incorporated, Hartford, Conn., a
corporation of Connecticut

Application August 16, 1944, Serial No. 549,673

2 Claims. (Cl. 133—8)

1

The present invention relates to means for counting the number of coins or tokens which are fed through a chute of a vending machine or other coin controlled or prepayment apparatus. The aim of the invention is to provide coin counting means of this character having various features of novelty and advantage and which is particularly characterized by its simplicity in construction, its economy in manufacture and its reliability in operation.

A further aim of the invention is to provide an improved arrangement wherein the coins themselves, as they pass through the chute, drive the counter so that no manual operation, aside from that of inserting the coins into the chute, is required to effect a registration.

A still further object of the invention is to provide a mechanism of this sort wherein the coin last to drive the counter is held in a position where it may be observed through a window and such coin is released by the next succeeding coin as the latter advances the counter one digit.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawings, wherein is shown, for illustrative purposes, one embodiment which the present invention may take:

Figure 1 is a front view of the chute to which my invention is applied;

Fig. 2 is a rear elevational view thereof;

Fig. 3 is an edge view of the mechanism as viewed from the left, referring to Fig. 1;

Fig. 4 is an edge view thereof as seen from the right, referring to Fig. 1;

Figs. 5 and 6 are sectional views taken on horizontal planes through the chute, these views being taken substantially on the lines 5—5 and 6—6 respectively;

Fig. 7 is a vertical sectional view through the chute taken substantially on line 7—7 of Fig. 5 and shows a coin in that position where it may be observed through the sight opening or window; and

Fig. 8 shows a succeeding coin in the act of tripping the latch 26.

Referring to the drawings in detail, A denotes generally a coin chute only so much thereof being shown as is necessary to illustrate the present invention. The chute may be associated with any

2

suitable coin controlled or coin operated mechanism, the same not being disclosed. For example, the chute may be employed to deliver coins to a coin controlled liquid dispensing apparatus. 5 The upper end of the chute may be provided with any suitable device for throwing out spurious coins or tokens.

In the present illustrated disclosure, the chute has a front plate 12 provided on its rear face 10 with two parallel ribs 14, the opposed edges of which form the side edges of the coin or token passage 10. The rear wall of the chute comprises the plates 16 which may be secured to the ribs by screws 18. The rear wall of the chute has a 15 semi-circular opening 19 which accommodates the driving member 20 of the counter 21. This driving member is here shown as being in the form of a disk having on its front face coin engaging members or abutments in the form of pins 22. In the present instance, the pins are five in number, are equally spaced apart, and are disposed adjacent the perimeter of the disk. One 20 of the ribs 14 is grooved, as at 23, so as to accommodate these pins during the step-by-step rotation 25 of the disk.

The edge of the disk is provided with notches 24 corresponding in number and spacing to the pins 22. The trailing edges 25 of these notches are radially disposed so as to form shoulders 30 with which cooperates the tooth 30 of a latch 26. The latch is pivoted at its upper end to one of the ribs by a screw 28. This latch has, intermediate its ends, an ear 32 which is offset forwardly so as to extend into one side of the coin 35 passage 10. The rib to which the latch is pivoted has a transverse groove 33 which accommodates this ear. The inner edge of this ear is inclined downwardly and inwardly of the chute so as to provide a cam surface 34 against which a coin 40 is adapted to bear, as shown in Fig. 8, so as to move the latch to the released position shown 45 therein. The latch is urged towards the periphery of the disk by a compression spring 36 mounted in a groove provided in a boss 38 on the front plate 12. The upper rear plate 16 is cut away or notched, as at 40, so as to accommodate the latch. The lower plate 16 has, at its upper end, a rearwardly offset ear 42 which serves to guide the lower end of the latch and also to close the 50 groove in which the spring 36 is mounted. The front wall of the chute is provided with a window 44 or sight opening through which the coins, when they reach the position shown in Fig. 7, may be observed.

55 The counter or registering mechanism 21 may

be of any suitable type, it here being shown conventionally as having a casing within which are a plurality of numeral wheels 45 between which any suitable transfer means (not shown) may be provided. These wheels are mounted on a shaft 47. The counter has a drive shaft 48 which may be geared to the wheel of lowest order in a one to two ratio. The driving disk 20 is fixed to this shaft 46. The counter is mounted on a bracket 48 which is secured to the rear face of the front wall 12 by means of screws 50.

The operation of the device will be readily understood from an examination of Figs. 7 and 8. In Fig. 7, the coin, which is disclosed for illustrative purposes as comprising a Jefferson nickel or five-cent piece, is shown as being held in a position where it is behind the window or sight opening 44. The pin which supports this coin is in coin holding position adjacent the right hand edge of the passage. When the coin moved through the chute to that position, it first engaged the cam edge 34 so as to release the disk from the latch and then, through its engagement with the pin 22 therebeneath, advanced the disk to the position shown. The disk was stopped in this position by the latch which was automatically moved into the latching position shown by the spring 36. Fig. 8 shows a second coin passing through the chute, this coin being illustrated as an Indian-head nickel or five-cent piece for purposes of distinction only. This nickel is shown in the act of tripping the latch, and it will now move down to engage the left hand pin 22 (which is in coin receiving position) so that the weight of this coin, together with the weight of the first coin, will serve to drive the disk one step. During such step movement of the disk, the Jefferson nickel is released from the position shown and will drop down through the chute to a receptacle or coin controlled mechanism (not shown). The disk, of course, is stopped by the latch in a position in which the Indian-head nickel is held in registry with the window. It will be observed that the pins are so located that they do not interfere with the engagement of the coin with the cam 34 of the latch. The pin, when in coin receiving position, is initially in the horizontal plane which includes the axis of the disk so that, when the coin engages the pin, maximum leverage is obtained to set the disk into rotation, and when the disk is stopped by the latch, the pin is in a position to hold the coin between itself and the opposing side edge of the passage 10 in registry with the window or sight opening. Upon each step rotation of the disk, the numeral wheel of lowest order of the counter will be advanced one digit.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of

the scope of the invention which, as a matter of language, might be said to fall therebetween.

I claim as my invention:

1. In a device of the character described, a coin chute having a downwardly extending passage corresponding in cross section generally to the cross sections of the coins, an element arranged to be driven by the weight of the coins passing through said passage, said element comprising a rotary disk partially located in the rear wall of the passage and a plurality of pins projecting from the front face of the disk and adapted to be engaged by the coins, said pins being angularly spaced-apart and each having within the passage a coin receiving position adjacent one side edge of the passage and a single temporary coin holding and exhibiting position therebeneath adjacent the opposite edge of the passage, said disk having stop shoulders, and a pivoted latch located adjacent the first-mentioned side edge of the passage and having a tooth adapted to engage said shoulders and a downwardly and inwardly inclined cam portion projecting into said passage above the coin receiving position of said pins and adapted to be engaged and cammed outwardly from said passage by a coin passing therethrough to disengage the tooth from said shoulders whereby the coin is permitted to move to held and exhibited position while the prior coin is released.
2. In a device of the character described, a coin chute having a substantially straight downwardly extending passage, a rotary element arranged to be driven by the weight of coins in said passage, said element comprising a disk having a plurality of coin receiving pins spaced-apart adjacent the periphery thereof and each adapted to be rotated with said element into a coin receiving position within the passage and a single coin holding and exhibiting position therebeneath, means for permitting said disk to rotate one step for each successive coin moving through said passage and into engagement with a said pin in coin receiving position thereby moving said successive coin to exhibited position and releasing the prior coin; said means comprising shoulders on said disk, latch means cooperating successively with said shoulders and urged into cooperation with said shoulders by a spring, and a cam associated with said latch and extending into said passage above said coin receiving pin and adapted to cam said latch out of engagement with said shoulders by the weight of a coin as it moves downwardly in said passage.
